UNITED STATES PATENT OFFICE.

SAMUEL W. RUSHMORE, OF PLAINFIELD, NEW JERSEY.

EXPLOSIVE SHELL.

1,297,499.

Specification of Letters Patent. Patented Mar. 18, 1919.

Application filed June 15, 1918. Serial No. 240,121.

To all whom it may concern:

Be it known that I, SAMUEL W. RUSHMORE, a citizen of the United States, and resident of Plainfield, in the county of Union 5 and State of New Jersey, have invented certain new and useful Improvements in Explosive Shells, of which the following is a specification.

High explosive shells employed in modern 10 warfare are usually exploded by graze or percussion fuses. In soft or wet ground the shells, depending upon their size and velocity and the type of fuse employed, penetrate from a foot to twenty feet or more before 15 exploding and the explosive force is largely dissipated in scattering the earth to form craters of from a few feet to fifty feet in diameter. Therefore, against personnel and equipment, these shells are almost ineffective 20 and the danger area is but little greater than that of the craters.

The purpose of the present invention is to provide a shell with an extension to the forward end so arranged as to cause the detonation of the explosive charge while the 25 shell is still above the ground or, at least, before it has penetrated to an appreciable depth.

Attempts have been made to employ extension pieces fitted with extended firing pins to be actuated by the usual contact button, but it has been found that, with any 30 considerable extension, the firing pin or rod is subject to an enormous "set back" or 35 inertia stress induced by the tremendous rate of acceleration when the shell is fired from the gun so that attempts to lengthen the fuse by increasing the length of the firing pin have proved to be failures.

My invention involves a combination of 40 parts whereby all of these difficulties are avoided and I have succeeded in combining standard tried and tested elements capable of producing the desired result with absolute certainty.

My invention depends upon certain fundamental discoveries which I will describe in connection with the particular size of shell and particular apparatus which has been actually tested by me under service conditions. 50 These discoveries are—

First, a standard six inch shell which is approximately 22 inches long, will carry an elongated projection or nose as long or 55 longer than the shell itself and this projection can be made heavy enough to stand all

set back and stress of regular service firing without materially affecting the accuracy of firing. In a particular case, firing at long range the service shells provided with my 60 long fuse would group within a circle not more than two or three times the circle shown by groups of the standard shells with standard fuse fired under the same conditions.

Second, placing of percussion fuses at the end of such projection is as safe and free from liability of premature explosion as when the fuse is directly on the tip of the shell.

Third, it has been denied that an explosive wave of condensation will be propagated in air fast enough to produce the desired effect in a fuse, but I have discovered that I can, by suitable arrangements, add to 70 the compression wave, a shot gun effect due to flying particles of metal, the speed of which is entirely independent of air pressure propagation and is in fact rapid enough so that for my purposes it may be considered 75 as instantaneous.

These three discoveries make my invention possible.

The apparatus employed is substantially standard and hence the description of the 85 device as actually constructed by me may be very brief. A device substantially as used by me is shown in the accompanying drawings, in which—

Figure 1 is a side elevation of a shell having the proportions of a 6 inch shell with my fuse in position thereon;

Figs. 2 and 3 are longitudinal sections showing the standard element which I employ and the way in which I combine them, 95 Fig. 2 showing the shell end and booster arrangements and Fig. 3, the contact fuse arrangements, the intermediate parts being broken away; and

Fig. 4 is a similar view showing a modified form of the parts shown in Fig. 3.

The shell 1, say 22 inches in length is provided with a fuse tube 2 which, as before explained, may be approximately as long or even longer than the shell. The fuse tube is 105 secured to the shell by the enlarged base 3 exteriorly screw-threaded at 4 to fit the standard shell. This part of the construction is standard as to the drawn steel shell 5 containing a booster charge of tetryl at the 110 forward end 6 and T. N. T. at the rear end 7, both compressed to say 5000 pounds per

square inch; also the drawn metal cup 8 secured to a washer 9 preferably by soldering and separated from the tetryl by a compressed washer 10. The cup 8 is designed to receive the rear end of the ordinary standard fuse and I preferably utilize such construction for my present purpose. It consists of a brass shell 11 inclosed by a copper cap 12 containing a charge of fulminate of mercury 13 protected by an inner shell 14, preferably of drawn copper. The latter is held in place by a felt washer 15 slightly compressed by the brass bushing 16. The latter, as first employed by me, was actually cut from the rear end of a standard instantaneous fuse similar to that known in the United States service as "mark III," but as used by me, the interior has been coned as at 17 for a purpose explained hereafter.

20 The fuse tube is formed with a central bore 18 having fitted into the forward end thereof an instantaneous fuse which may be in all respects identical with a complete fuse of the "mark III" type, the rear end comprising parts identical with parts 10 to 16 previously described. In this complete fuse, the fulminate charge 13' is detonated in the usual way. The mechanism for this purpose includes a shell 20 containing a small charge of fulminate 21, protected by a shell 22, held in place by felt washer 23. Alined with the center of the charge is a firing pin 24 secured to plunger 25 having a contact head 26 normally held in forward position by a metallic ribbon 27 spirally wound between the head and the washer 28 and provided with centrifugal weight 29 whereby it is thrown off and unwound as soon as the shell leaves the gun. The enormous strain 40 of the "set back" having been resisted by the metallic ribbon and the latter removed, the plunger is held in its forward position only by the shear pin 30, which will be sheared off upon contact of the head 26 with even the slightest obstruction.

45 The firing pin sets off the fulminate 21 which detonates the fulminate charge 13' which shatters the copper shell and brass casing, driving the particles thereof with enormous velocity, like a charge of shot, rearwardly down the passage or gun barrel 18 and is concentrated by the cone passage 17 upon the fulminate charge 13 which explodes the booster charge.

50 As before stated, my experiments demonstrate that the shot gun effect is substantially instantaneous and effective. It enables me to have standard fuse arrangements on the front end of the long fuse tube without having any physical operating parts such as a long firing pin to introduce the complications which have rendered prior proposed devices inoperative.

In Fig. 4 I have shown the passage 18' contracted to the same diameter as the brass

case of the detonator so as to reduce the proportions of the bore more nearly to those of a rifle, with the case contacting with the breech which is thickened as at 30 to reinforce it against the explosion and to insure 70 that the shot will be confined and take effect entirely rearward. This makes possible the use of a thinner barrel for the intermediate portion of the fuse tube.

Tests with a 6 inch shell show that with 75 the above described combination of parts the shell will explode well above the ground even when fired into ordinary soft earth.

I claim:

1. An ordnance shell having a projection 80 secured to the forward end thereof extending axially, and formed with a longitudinal bore in combination with a contact fuse having a detonating charge in alinement with the bore of said projection; and, at the rear 85 end a similar detonating charge in operative relation to the booster charge of the shell, and communicating with and in alinement with the said passage.

2. A structure such as described in claim 90 1, having the passage to the booster detonator coned to concentrate the effects of the explosion of the fuse detonator.

3. An ordnance shell having a projection 95 at the forward end thereof extending axially and formed with a longitudinal passage, in combination with a contact fuse having its detonating charge in operative relation to the forward end of said passage, and a second detonating charge at 100 the rear end of said passage in operative relation to the explosive charge of the shell.

4. An ordnance shell having a projection at the forward end thereof formed with a longitudinal passage therethrough, in combination with a contact fuse mounted on the forward end of said projection and having a detonating charge in operative relation to the forward end of said passage; and a similar detonating charge in 110 operative relation to the rear end of said passage and to the explosive charge of the shell.

5. An ordnance shell having a projection at the forward end thereof formed with a 115 longitudinal passage therethrough, in combination with a contact fuse mounted on the forward end of said projection and having a detonating charge in operative relation to the forward end of said passage; and a second detonating charge in operative relation to the rear end of said passage and to the explosive charge of the shell; the walls of said projection, the passage therethrough, the contact fuse and the 120 detonating charges being substantially symmetrical with respect to the axis of the shell and having their axes in alinement with each other and with said axis of the shell so that the centrifugal forces due to 130

axial rotation of the shell when it is fired, will be balanced in each cross-section of the device.

6. An ordnance shell having a projection at the forward end thereof formed with a longitudinal passage therethrough, in combination with a contact fuse mounted on the forward end of said projection and having a detonating charge in operative relation to the forward end of said passage; and a second detonating charge in operative relation to the rear end of said passage and to the explosive charge of the shell, said projection being tapered from the shell toward the forward end and, at the outer end, having its walls of material and thickness sufficient to confine the fuse detonator explosion against material, lateral expansion.
7. An ordnance shell having an explosive charge and means for detonating it, said means including an axially arranged tubular projection at the forward end of the shell, a detonating charge in alignment with the rear end of the passage through said projection and in operative relation to the explosive charge in the shell; and, in alignment with the forward end of said passage, another detonating charge and means for detonating the latter including a contact firing pin, the total distance from the shell detonating charge to the forward contact surface of the firing pin being approximately as great as the length of the shell and the length of the firing pin covering only a practically negligible portion of said distance.
8. An ordnance shell having an explosive charge, a detonating charge in operative relation thereto and a contact fuse having another detonating charge and means in-

cluding a short firing pin for detonating the latter, in combination with a tubular forward extension for the shell of small diameter, light weight and considerable length as compared with the shell, said extension having said contact fuse secured at the forward end thereof and having a tubular cavity extending in a straight line from the shell detonator to the fuse detonator, the length of said passage being predetermined with reference to the normal velocity of the shell for the purpose and with the result of exploding the shell substantially in advance of the object which operates the firing pin.

9. An ordnance shell having an explosive charge and means for detonating it, said means including a tubular member, detonating charge in alignment with the rear end of the passage through said tubular member and in operative relation to the explosive charge of the shell; and, in alignment with the forward end of said passage, another detonating charge and means for detonating the latter including a contact firing pin, the length of said passage and the distance of the fuse detonating charge in advance of the shell detonating charge being predetermined with reference to the normal velocity of the shell and the normal time interval between firing pin contact and shell explosion, for the purpose and with the result of substantially advancing the position of explosion of the shell with reference to the object which operates the firing pin.

Signed at New York city, in the county of New York and State of New York, this 14th day of June, A. D. 1918.

SAMUEL W. RUSHMORE.
